Primary Examiner — John Windmuller*Assistant Examiner* — John R Yeh*(74) Attorney, Agent, or Firm* — McGinn IP Law Group, PLLC(57) **CLAIM**

The ornamental design for hose clamp, as shown and described.

DESCRIPTION

FIG. 1 is a perspective view of a hose clamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures are included for the purpose of illustrating the unclaimed portions of the hose clamp and form no part of the claimed design. The dot-dash lines define the bounds of the claimed design and form no part thereof.
